UNITED STATES PATENT OFFICE

JOZEF BAGEL, OF CHICAGO, ILLINOIS

PROPELLER

Application filed March 3, 1931. Serial No. 519,735.

My invention relates to improvements in propeller construction and is more particularly concerned with the provision of an improved propeller provided with blades that rotate around a common axis, presenting their faces transversely during a part of their rotary motion and presenting their face to the plane of rotation during other parts of their rotation.

The invention has reference generally to an improved construction of a feathering paddle-wheel or propeller for marine propulsion; and the invention has for its principal object to provide a simple, compact and strong construction of paddle-wheel or propeller known as "feathering wheels" wherein each blade or paddle is made to present its face transverse to the line of motion during some certain part of its revolution, or while such position would assist in propulsion, and during the balance of its revolution the face of the blade or paddle is turned so as to be in the plane of its rotary movement, and thus offer a minimum of resistance. The paddle-wheel or propeller thus operating is intended to be rotated under water, in other words while submerged.

A further object of the present invention is to provide such a feathering paddle-wheel or propeller capable of being attached to a rowboat or other craft, propulsion of which is desired.

A further object is to provide an improved propeller or fan of this general description capable of use for drawing a current of air through a tube, for driving an aeroplane, or for use in any other suitable manner.

Other objects and advantages will be more apparent in connection with the following description, reference being had to the accompanying drawings in which

Fig. 1 is an elevational view of a boat, showing my improved propeller in one embodiment thereof;

Fig. 2 is an enlarged side view thereof;

Fig. 3 is an end view on the same scale;

Fig. 4 is a horizontal sectional view taken generally on line 4—4 of Fig. 2;

Fig. 5 is a similar view showing a changed position of the propeller blades and

Fig. 6 is an enlarged vertical section showing the drive connection.

Referring to the drawings in Fig. 1, I have shown a boat or vessel 10 in which a motor (not shown) may be provided for driving the propeller shaft 12 which extends rearwardly from the interior of the boat. The shaft 12 extends through a supporting bracket 14 from which the propeller unit "A" which forms the subject matter of this invention is supported.

The propeller shaft 12 carries at its extended end a bevel gear 16 locked thereto by the taper pin 18. The bevel gear 16 is spaced from the bracket 14 by a suitable spacer washer 20. Bracket 14 is secured to the end of boat 10 by suitable bolts 21.

The bracket is adapted to support a plurality of vertically disposed tubular shaft members, and accordingly has one arm 22 extending at right angles at its upper end, another arm 24 extending at right angles at its lower end. Arm 24 is adapted to be attached to the hub of a stationary gear pinion 26 by suitable fastening means 28.

A vertical supporting rod 30 is secured through a suitable opening in arm 22 by the bolt and nut connection 32 and extends downwardly. A pair of gear pinions 34 and 36 are adapted to be mounted at opposite sides of, and meshing with the bevel gear 16. Pinion 34 is mounted and keyed to a tubular shaft 38 which is mounted on rod 30 and extends downwardly. Pinion 36 is likewise provided with an axial bore and is mounted upon tubular member 38. Gear pinion 36 has a tubular hub 40 extending downwardly through a suitable opening 42 in the pinion 26. Vertical rod 30 extends downwardly below pinion 26 and carries at its lower end a stationary gear pinion 44 which is fastened to the rod by the set screw 46. Pinion 44 has an upwardly extending hub portion 48 which furnishes a lower abutment for the tubular member 38. Tubular member 38 carries a collar 50 secured thereto by set screw 52 which forms a lower abutment for the hub portion 40 of pinion 36. Both hub portion 40 and tubular member 38 have a horizontal stub shaft 54 fastened thereto by set screws 56.

Fig. 1 is an elevational view of a boat, showing my improved propeller in one embodiment thereof;

Fig. 2 is an enlarged side view thereof;

Fig. 3 is an end view on the same scale;

Fig. 4 is a horizontal sectional view taken generally on line 4—4 of Fig. 2;

Fig. 5 is a similar view showing a changed position of the propeller blades and

56. Each of these stub shafts carry a bevel gear 58 to the hub of which a propeller vane 60 is rigidly fastened. These propeller vanes may be of any particular shape desired, and for the purpose of this disclosure they have been shown substantially as flat extended paddles having an opening 62 near the hubs 64 of the bevel gears 58.

The operation of my improved propeller 10 means will now be described. When the shaft 12 is rotated bevel gear 16 will rotate pinions 34 and 36 in opposite directions. These bevel gears carry upon angularly extended stub shafts the large gears 58 and 15 revolve these gears in opposite directions about the same axis.

As these gears 58 are in mesh with the stationary pinions 26 and 44 they will likewise be rotated, as they travel in their path 20 of revolution about their axis.

As shown in Figs. 2, 3, and 4, and indicated by the arrows on Fig. 4 during that part of their rotation shown in Fig. 4 the blades will have a tendency to force water or any other substance in which they may be submerged 25 away from the blades. Thus for example, forcing a boat upon which the unit "A" may be positioned, forward during that part of their revolution. In Fig. 5 the blades have 30 traveled 180° in their horizontal circular path and have also turned approximately 90° so that when each blade has traveled 270° as shown in the dotted line position the blades will be inclined and during the further 90° 35 rotation they will again assume a vertical position to exert forward "push" during the next part of their rotation.

Due to the connection between gears 26, 44, 40 and the two gears 58 it can thus be clearly seen that the propeller blades 60 are driven in opposite directions. That is, one revolves clockwise and the other revolves anti-clockwise, as clearly shown in Figs. 4 and 5. The forward movements of the boat is obtained 45 when the blades 60 are aligned vertically in Fig. 5 as shown in the dotted line and from this point to where they assume a horizontal position, as shown in full lines in Fig. 5.

Thus it will be seen that forward impetus 50 is given to the boat during a portion of the revolution of the blades around their axis.

As clearly shown in the drawings the gears 26 and 44 are exactly the same size, as also 55 are the gears 58, so that the gears 58 are both revolved at the same rate of speed. Proportionate sizes of gears 58 as compared to gears 26 and 44 should be such that gears 58 make one-half complete revolution while 60 turning around the axis.

It should be borne in mind that this propeller construction may be employed for example as a fan to propel air through a conduit such as shown at "B" in dotted line in 65 Fig. 5.

I am aware that some changes may be made in the arrangements and combinations of the various devices and parts, as well as in the details of the construction of the same, without departing from the scope of the present invention as set forth in the foregoing specification and as illustrated in the accompanying drawings, nor do I confine myself to the exact details of the construction of the said parts. 70

I claim:

1. A feathering wheel of the type described comprising, a vertical supporting rod, a bracket therefor, a stationary pinion secured to the lower end of said rod, a similar pinion through which said rod extends mounted above said pinion on said bracket, a pair of tubular shafts, mounted on said rod in axial alignment, a bevel gear carried by each shaft and engaging said stationary pinions, a horizontally extending propeller blade secured to the hub of each of said bevel gears and driving means for horizontally rotating said bevel gears in opposite directions, said blades being adapted 80 to be brought to a feathering position during a portion of each revolution by said stationary pinions. 85

2. A feathering wheel of the type described comprising, a vertical supporting rod, a bracket therefor, a stationary pinion secured to the lower end of said rod, a similar pinion through which said rod extends mounted above said pinion on said bracket, a pair of tubular shafts, mounted on said 90 rod in axial alignment, a bevel gear carried by each shaft and engaging said stationary pinions, a horizontally extending propeller blade secured to the hub of each of said bevel gears, a collar for vertically positioning 95 said bevel gears, and driving means for horizontally rotating said bevel gears in opposite directions, said blades being adapted to be brought to a feathering position during a portion of each revolution by said stationary pinions. 100

3. A feathering wheel of the type described comprising, a vertical supporting rod, a bracket therefor, a stationary pinion secured to the lower end of said rod, a similar pinion through which said rod extends mounted above said pinion on said bracket, a pair of tubular shafts, mounted on said rod in axial alignment, a bevel gear carried by each shaft and engaging said stationary pinions, a horizontally extending propeller blade secured to the hub of each of said bevel gears, a pinion secured to each of said tubular shafts at their upper ends, a bevel gear engaging both pinions for rotating said shafts in opposite directions, said propeller blades adapted to be brought to a feathering position during a part of each revolution 110 by said stationary pinions. 115

4. A feathering wheel of the type described comprising, a vertical supporting rod, a bracket therefor, a stationary pinion secured to the lower end of said rod, a similar pinion through which said rod extends mounted above said pinion on said bracket, a pair of tubular shafts mounted on said rod in axial alignment, a bevel gear carried by each shaft and engaging said stationary pinions, a horizontally extending propeller blade secured to the hub of each of said bevel gears, a pinion secured to each of said tubular shafts at their upper ends, a bevel gear engaging both pinions for rotating said shafts in opposite directions, a driven shaft secured thereto, said propeller blades adapted to be brought to a feathering position during a part of each revolution by said stationary pinions.

20 5. A propeller of the type described comprising a supporting bracket, a driven shaft extending therethrough, a bevel gear on said shaft, a pair of pinions engaged by said bevel gear and driven in opposite directions, said pinions secured to telescoped tubular shafts extending downwardly therefrom in axial alignment, a pair of bevel gears rigidly secured to said tubular shafts, propeller blades secured to said bevel gears, and stationary gear pinions engaging said bevel gears whereby said blades are rotated around a common axis, and arranged to alternately present their faces to the plane of rotation and lie transverse to the plane of 35 rotation as and for the purpose described.

6. A propeller of the type described comprising a supporting bracket, a driven shaft extending therethrough, a bevel gear on said shaft, a pair of pinions engaged by said bevel gear and driven in opposite directions, said pinions secured to telescoped tubular shafts extending downwardly therefrom in axial alignment, a bevel gear rigidly secured to each of said tubular shafts, a propeller blade 40 secured to the hub of each of said bevel gears, a stationary pinion engaging each of said bevel gears, whereby when said blades are rotated around their common axis, the blades are turned to alternately present their 45 faces to the plane of rotations and to lie transversely to the plane of rotation as and for the purpose described.

In testimony whereof I affix my signature.
JOZEF BAGEL.
